Attorney, Agent, or Firm—Pepe & Hazard LLP

[57] CLAIM

The ornamental design for a blade holder, as shown and described.

DESCRIPTION

FIG. 1 is a side elevational view of a blade holder showing our new design;

FIG. 2 is a side elevational view of the opposite side;

FIG. 3 is a bottom plan view thereof;

FIG. 4 is a top plan view thereof;

FIG. 5 is a front end elevational view thereof; and,

FIG. 6 is a rear end elevational view thereof.

The stippled portions reflect a difference in texture and/or color from the remainder of the design.
